UNITED STATES PATENT OFFICE.

ARTHUR RAYNSFORD, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,399,998.

Specification of Letters Patent. Patented Dec. 13, 1921.

Application filed November 25, 1919. Serial No. 340,484.

To all whom it may concern:

Be it known that I, ARTHUR RAYNSFORD, a citizen of the United States, residing at New York, in the county of New York, 5 State of New York, have invented certain new and useful Improvements in Telephone Systems, of which the following is a full, clear, concise, and exact description.

This invention relates to telephone systems and more particularly to improved 10 signaling arrangements for such systems.

It is the object of this invention to provide in a link circuit with which connections may be established through different 15 types of cord circuits, means responsive to the disestablishment of a connection at the answering end of the link circuit for operating a signaling device associated with the particular cord circuit employed in establishing 20 the connection.

In the present embodiment of this invention there is provided a link circuit terminating at one end in multiple jacks at an operator's position and at the other end in the springs of an operator's listening key. Two types of cord circuits are provided for use in establishing connections with this 25 link circuit. One of these cord circuits is of the type which may be used for connecting with central energy trunk lines and is provided with a polarized supervisory relay which controls a disconnect signal. The other cord circuit is of the type which may be employed in connection with magneto or 30 toll trunk lines and is provided with an alternating current supervisory relay to control a disconnect signal. The insertion of the plug of either of these cord circuits in the jack of the link circuit controls 35 relay associated with the link circuit to select the type of current which will operate the supervisory relay in the cord circuit being used, so that when the connection is disestablished the selected current is impressed 40 upon the link and cord circuits to operate the supervisory relay of the cord circuit to give a disconnect signal.

In the drawing are shown two plugs which may be those at one end of the respective cord circuits described, or may be at opposite ends of a single cord circuit which may be employed with either magneto or central energy lines. A link circuit is shown leading from multiple jacks to an 45 operator's listening key.

It is believed that the invention will be readily understood from a consideration of the operation of the system, which is as follows: An operator who has answered a call from a central energy station 32 with 50 that end of the cord circuit 1 which is not shown in the drawing, desiring to extend the connection to a supervisory operator, inserts plug 2 in jack 3 of the link circuit leading to the supervisory operator's position and operates her ringing key to close the alternate contacts of key springs 4 and 5. Upon the insertion of the plug in the jack a circuit is completed from grounded battery through the winding of sleeve relay 6, sleeve contacts of plug 2 and jack 3, through the windings of relay 7 and marginal relay 8 to ground. Relay 6 has a low 55 resistance winding and permits sufficient current to flow over the circuit traced to 75 energize relays 6 and 7 and marginal relay 8. In operating the ringing key a circuit is completed from a source of alternating current, alternate contact of spring 5, ring contacts of plug 2 and jack 3, ring conductor 9, conductor 10, right-hand armature and back contact of relay 11, conductor 12, through the ringer at the supervisory operator's position, condenser 13, tip conductor 14, tip contacts of jack 3 and plug 2, and alternate contacts of spring 4 to ground. The supervisory operator, hearing the bell which is rung in the circuit traced, depresses 80 her listening key 15, including her telephone set in the line circuit, and completing a circuit from ground, contact 16, through the winding of relay 17 to grounded battery, to operate relay 17. Relay 17 in attracting its left-hand armatures disconnects the battery which was connected to 85 conductors 14 and 9 through impedance coil 18 by the operation of relay 8, and in attracting its outer right-hand armature completes a circuit from grounded battery, outer right-hand armature and front contact of relay 17, through the winding of 90 relay 19 and normal contact of holding key 20 to ground. Relay 19 is operated in this circuit and locked up through its front contact and left-hand armature to grounded 95 battery at the armature of relay 7. In attracting its right-hand armature relay 19 completes an energizing circuit for slow release relay 21 from grounded battery 100 through the winding of relay 21, right-hand 105 armature and front contact of relay 17. Relay 21 completes an energizing circuit for slow release relay 22 from grounded battery 110 through the winding of relay 22, right-hand armature and front contact of relay 17.

armature and front contact of relay 19, front contact and inner right-hand armature of relay 17 to ground. Relay 21 in operating completes an energizing circuit 5 for relay 11. In attracting its right-hand armature relay 11 interrupts the ringing circuit, and the supervisory operator may now converse with the calling party at station 32, talking current being supplied 10 from a battery 33 associated with the calling line of which the free pole is connected through a winding of impedance coil 34 to the ring side of the line, and the grounded pole through another winding to the tip 15 side of the line. Current of this polarity flowing through the line will not operate polarized relay 22 associated with the cord circuit.

At the conclusion of the conversation the 20 supervisory operator in releasing key 15 opens contact 16, thereby interrupting the circuit for relay 17, which deenergizes to complete a circuit from grounded battery through the left-hand winding of impedance 25 coil 18, front contact and inner armature of marginal relay 8, back contact and outer left-hand armature of relay 17, conductor 14, tip contacts of jack 3 and plug 2, normal contact of spring 4, through the winding of 30 relay 22, normal contact of spring 5, ring contacts of plug 2 and jack 3, conductor 9, inner left-hand armature and back contact of relay 17, outer armature and front contact of relay 8, through the right-hand winding 35 of impedance coil 18 to ground. The current flowing in this circuit is of the proper polarity to energize the cord circuit polarized supervisory relay 22, which attracts its armature to complete a circuit from grounded battery, front contact and armature of relay 6, lamp 23, front contact and armature of relay 22 to ground. Lamp 23 is lighted 40 in this circuit to indicate to the operator that she may remove plug 2 from jack 3. 45 In removing plug 2 from jack 3 the circuits of relays 6, 7, 8 and 22 are interrupted and these relays retract their armatures. Relay 6 opens the circuit of lamp 23 which is extinguished. Relay 7 opens the locking 50 circuit of relay 19 which thereupon retracts its armatures and the system is completely restored.

If an operator has answered a call from a magneto station 35 with one end of a cord circuit 24 and desires to extend the connection to a supervisory operator, she inserts plug 25 in jack 3 and depresses the ringing key associated with cord 24 to close the alternate contacts of springs 26 and 27. The insertion of the plug in the jack completes a circuit from grounded battery through the winding of sleeve relay 28, sleeve contacts of plug 25 and jack 3, windings of relay 7 and marginal relay 8 to ground. Relay 28 60 has a resistance sufficiently high to prevent

the energization of marginal relay 8 in this circuit, but relays 28 and 7 are energized. Relay 28 prepares a circuit for lamp 29, and relay 7 prepares a locking circuit for relay 19, as when cord 1 was employed. In depressing her ringing key the operator completes a circuit to ring the call bell of the supervisory operator, which may be traced from a source of alternating current, through the alternate contact of spring 27, ring contacts of plug 25 and jack 3, conductor 10, right-hand armature and back contact of relay 11, conductor 12, through the supervisory operator's call bell and condenser 13, conductor 14, tip contacts of jack 3 and plug 25, and alternate contact of spring 26 to ground. The supervisory operator responds by depressing her key 15 to include her telephone set in the line circuit and close contact 16. Relay 17 is energized and completes the previously traced circuit for relay 19, which locks up over the circuit previously traced and energizes slow release relay 21 in the manner already described. Relay 21 completes a circuit for relay 11 which thereupon attracts its armatures. In attracting its right-hand armature relay 11 interrupts the ringing circuit, and in attracting its left-hand armatures connects ground and a source of alternating current to the back contacts of the left-hand armatures of relay 17, so that when this relay is subsequently deenergized, alternating current will flow over the line.

Should the supervisory operator desire to hold the connection while answering another call, she might operate her holding key 20. The operation of key 20 provides a substitute circuit for relay 17 to prevent the source of alternating current from being connected to the line, but interrupts the holding circuit of relay 19 which is deenergized to open the circuit of relay 21. Relay 21 in retracting its armature opens the circuit of relay 11, which is deenergized. When the operator desires to continue the conversation, she again depresses her listening key and releases her holding key. The closure of the normal contact of key 20 again completes the circuit for relay 19 which operates relays 21 and 11 as before. At the conclusion of the conversation the operator releases her listening key 15, disconnecting her telephone set from the link circuit and opening contact 16. Relay 17 is deenergized to complete the circuit from the source of alternating current, front contact and inner left-hand armature of relay 11, back contact and outer armature of relay 8, back contact and inner left-hand armature of relay 17, conductor 9, ring contacts of jack 3 and plug 25, normal contact of spring 27, through the left-hand winding of relay 30, condenser 31, normal contact of spring 26, tip contacts of plug 25 and jack 3, conductor 14, outer left-hand

armature and back contact of relay 17, inner armature and back contact of relay 8, outer left-hand armature and front contact of relay 11 to ground. At the same time that this 5 circuit was completed relay 17, in retracting its inner right-hand armature, interrupted the circuit for relay 21. Relay 21 being slow to release maintains the circuit for relay 11 a sufficient length of time to allow 10 supervisory relay 30 to be operated in the circuit for alternating current just traced. Relay 30 in attracting its armature completes a locking circuit for itself and a circuit for lamp 29, so that lamp 29 is lighted 15 and remains so until the operator removes plug 25 from jack 3. In removing the plug from the jack the circuit for relays 28 and 7 is opened. Relay 28 in retracting its armature opens the circuit for lamp 29 which 20 is extinguished and the locking circuit for relay 30, which relay is thereupon deenergized. Relay 7 in deenergizing opens the locking circuit for relay 19 which becomes inert and the system is now completely 25 stored.

Thus by the use of sleeve relays of different resistance in association with cord circuits having supervisory relays responsive to different varieties of current, the proper 30 variety of current to operate the supervisory relay of each cord circuit will be automatically selected upon the insertion of the plug into the calling jack of a link circuit, and upon the subsequent interruption of the link 35 circuit the selected source of current will be connected over said link circuit to the cord circuit supervisory relay for a sufficient time to operate this relay to give a disconnect signal.

40 What is claimed is:

1. In a telephone system the combination with a link circuit, of a plurality of different types of cord circuits for connection therewith, a signaling device and a relay responsive to a particular variety of current 45 for operating said signaling device associated with each cord circuit, a telephone set, means for connecting said telephone set to said link circuit, a plurality of sources of current, and means operated in response to the disconnection of said telephone set from 50 said link circuit to connect one of said sources of current to said link circuit to operate the signaling device of the connected cord circuit.

2. In a telephone system the combination with a link circuit, of a plurality of different types of cord circuits for connection therewith, a signaling device and an operating relay therefor responsive to a particular variety of current for each of said cord circuits, a telephone set, means for connecting said telephone set to said link circuit, a plurality of sources of current, means responsive to the connection of any one of said cord circuits to said link circuit for selecting one of said sources of current, and means responsive to the disconnection of said telephone set from said link circuit for connecting the selected source of current to said link circuit to operate the relay of the connected cord circuit.

3. In a telephone system the combination with a link circuit, of a plurality of different types of cord circuits for connection therewith, a signaling device and an operating relay therefor responsive to a particular variety of current for each of said cord circuits, an extension for said link circuit, means for connecting said link circuit to said extension, a plurality of sources of current, means responsive to the connection of any one of said cord circuits to said link circuit for selecting one of said sources of current, and means responsive to the disconnection of said extension from said link circuit for connecting the selected source of current to said link circuit to operate the relay of the connected cord circuit.

4. In a telephone system the combination with a plurality of sources of current, of a plurality of cord circuits of different types, a disconnect signal and an operating relay therefor responsive to a particular variety of current from said plurality of sources for each of certain of said cord circuits, a disconnect signal and an operating relay therefor responsive to a different variety of current from said plurality of sources for each of others of said cord circuits, a link circuit, 100 a relay associated with said link circuit selectively responsive to the connection to said link circuit of each type of cord circuit to select and connect the proper source of current to actuate the operating relay of the 105 connected cord circuit.

In witness whereof, I hereunto subscribe my name this 21st day of November, A. D., 1919.

ARTHUR RAYNSFORD.
